UNITED STATES PATENT OFFICE.

ARTHUR B. LOW, OF DENVER, COLORADO.

TIRE-GAGE.

1,388,275.

Specification of Letters Patent. Patented Aug. 23, 1921.

Application filed April 12, 1918. Serial No. 228,251.

To all whom it may concern:

Be it known that I, ARTHUR B. Low, a citizen of the United States, residing at the city and county of Denver and State of Colorado, have invented certain new and useful Improvements in Tire-Gages; and I do declare the following to be a full, clear, and exact description of the invention, such as will enable others skilled in the art to 10 which it appertains to make and use the same, reference being had to the accompanying drawings, and to the characters of reference marked thereon, which form a part of this specification.

15 My invention relates to improvements in gages adapted for measuring fluid pressure, being more particularly intended for measuring the pressure in pneumatic tires of the class employed in connection with automobiles, bicycles, motorcycles, etc.

20 My object is to provide a gage, the bar of which is projected outwardly by the action of the fluid pressure on a plunger connected with the inner extremity of the gage bar and 25 on which the fluid acts, the plunger being retarded by friction alone, which friction gradually increases as the plunger moves outwardly, thus making it practicable to ascertain from suitable characters formed on 30 the gage bar and gradually increasing as they extend inwardly from the outer extremity of the bar, the pressure within the tire or other receptacle containing fluid as air or other gas under pressure.

35 The structure generally speaking consists of a tube through one extremity of which the gage bar projects a short distance normally, the entire numbered area however, of the bar being normally concealed. To the 40 inner extremity of the bar is secured the plunger whose outward movement is frictionally retarded, the shape of the tube being constructed to produce this result. Other provision within the tube may also be 45 made to effect the same result. The opposite extremity of the tube from that through which the outer extremity of the gage bar protrudes, is constructed to permit the access of air from the tube of the tire through 50 the medium of one or more perforations which are surrounded by such material as rubber, as will make it practicable to seal the casing of the tire valve while the part of the

gage in which the perforations are formed acts upon the valve stem to unseat the valve 55 pieces of the tire valve. The part of the device containing the perforations is preferably of metal which may be recessed or chambered, surrounding its central part to receive the elastic material adapted to seal 60 the casing of the tire valve during the use of the gage as just explained.

Any suitable provision may be made for gradually and uniformly increasing the degree of friction as the plunger forces the 65 gage bar outwardly, the plunger itself being acted on by the pressure of the fluid to be measured. The plunger is preferably perforated in order to allow the fluid pressure to pass inwardly and equalize on both sides of 70 the plunger except as to the cross sectional area of the gage bar. This is preferable for a number of reasons which will be herein-after fully set forth.

Having briefly outlined my improvement 75 I will proceed to describe the same in detail, reference being made to the accompanying drawing in which is illustrated several embodiments thereof. In this drawing:

Figure 1 is a central longitudinal section 80 of my improved gage.

Fig. 2 is a cross section taken on the line 2—2, Fig. 1.

Fig. 3 is a fragmentary, detail view of the 85 gage bar showing the plunger attached.

Fig. 4 is a fragmentary sectional view of the device shown on a somewhat larger scale and with a slightly modified form of plunger.

Fig. 5 is a section of the device similar to 90 Fig. 1, but showing a modified form of structure.

Fig. 6 is a cross section taken on the line 6—6, Fig. 5.

Fig. 7 is a central longitudinal section 95 illustrating another form of the gage, the gage bar being hollow and partly broken away.

Fig. 8 is a cross section taken on the line 100 8—8, Fig. 7.

Fig. 9 is a central longitudinal section of another form of the gage.

Fig. 11 is a similar view looking in the 105 direction of arrows 11, Fig. 9.

Fig. 12 is a view of Fig. 9 looking in the direction of arrows 12.

Fig. 13 is a central longitudinal section of the gage showing another form of construction.

Fig. 14 is a section taken on the line 14—14, Fig. 13 shown on a larger scale.

Fig. 15 is a section taken on the line 15—15, Fig. 13 also shown on a larger scale.

Fig. 16 is a sectional view of the base of the tube of the construction shown in Fig. 5 but on a larger scale.

Figs. 17 and 18 are central longitudinal sections of the gage showing other and distinct forms of construction.

Fig. 19 is a section taken on the line 19—19, Fig. 18.

Fig. 20 is a longitudinal section showing another form of construction.

Fig. 21 is a fragmentary perspective view of the gage bar and plunger illustrating the form disclosed in Fig. 20.

Fig. 22 is a longitudinal section showing another form of the device.

Fig. 23 is a cross section taken on the line 23—23, Fig. 22, the parts being shown on a larger scale.

Fig. 24 is a fragmentary perspective view in detail of the gage bar and showing a metal armored form of plunger.

Fig. 25 is a fragmentary perspective view in detail on a larger scale, showing one of the elements of the metal armor of Fig. 24.

Fig. 26 is a fragmentary sectional view in perspective of the upper part of the gage tube in one form of construction.

Fig. 27 is a perspective view of one member of the metal armor for the compressible material in the form of construction shown in Figs. 22 and 23 showing also the two disks in which the metal armor members are anchored and guided.

The same reference characters indicate the same parts in all the views.

Let the numeral 5 designate a tube which is depressed longitudinally on two opposite sides, the depressions gradually increasing in degree from the inner extremity 6 to the outer extremity 7 of the device, it being understood that the terms "inner" and "outer" are employed for convenience of description. These depressions which I will designate by the numeral 8 are inwardly, and their object is to gradually increase the

frictional resistance of a plunger 9 as the latter moves outwardly in the tube under the influence of fluid under pressure which enters through one or more perforations 10, Fig. 4, formed in the outer portion of a cup-shaped part 12 formed in a disk 4 which closes the inner extremity of the tube 5, a cap 13 being threaded upon the tube outside of the disk 4 and retaining in place a quantity of compressible material 14 as rubber, the cap having an opening 15 which is somewhat

larger than the part 12 of the disk in order to allow room for the casing of the tire valve to seal the latter during the use of the gage. The cup-shaped part 12 is provided internally with a quantity 16 of some suitable material adapted to form an air filter, whereby the air is prevented from carrying solid particles of appreciable size into the tube of the gage. It will be noted in Figs. 1 and 4 two perforations 10 are shown. The object of

70

a plurality of perforations is to make it impossible for both perforations to be sealed by the outer extremity of the stem of the tire valve during the use of the gage. It will be understood that as the perforated

80

part of the cup-shaped portion of the disk is applied to the outer extremity of the stem of the tire valve, the valve piece will be unseated allowing the air to enter the tube through one or both of the perforations 10.

85

In this form of the device the plunger 9 is constructed of some compressible material as rubber or rubber compound, the plunger being secured to the gage bar 17 by passing a reduced part 18 of the bar through the

90

center of the plunger and applying a nut 19 to the exposed threaded end of the said part. In this form exteriorly concave washers 20 and 21 are applied to the plunger on opposite sides, thus making it practicable

95

to regulate to some extent the size of the elastic or compressible plunger. It will be understood that as the nut 19 is tightened there will be a tendency to expand the plunger circumferentially. This plunger either

100

in its construction or in the manner of its connection with the gage bar must be fashioned to allow the fluid under pressure as air from the tire to pass into the chamber of the tube beyond the plunger or on the opposite side thereof from its entrance, whereby the effective action of the compressed fluid

105

on the plunger for fluid registering purposes is only upon an area of the plunger equal to the cross section of the gage bar 17.

110

This is an important feature since if the plunger sealed the structure against the entrance of air to the side of the plunger opposite its entrance, the pressure would be greater than desired and would require frictional resistance of too great magnitude, with the result that the frictionally engaging elements would be subjected to greater wear than is desirable.

115

Again, under the conditions stated, undue pressure on the outer end of the gage bar would be necessary in order to return the latter to its normal position after each fluid registering act. As shown in Fig. 1, the outer extremity of the tube is sealed around an opening 22 through which the gage bar passes by a gasket or cup-leather 23 which extends inwardly a short distance around the gage bar as shown at 24, the air pressure within the tube serving to seal the

120

chamber around the gage bar against the escape of fluid. This gasket or cup-leather is held in place in the outer extremity of the tube by an expansion member or spring ring

- 5 28. The outer extremity of the gage bar is preferably reduced in size, as shown at 25, leaving a point normally projecting beyond the tube which may be utilized in releasing the valve of the tire in case the valve 10 piece is stuck. This part 25 may also be advantageously employed in various other relations.

In using the form of device illustrated in Figs. 1 and 4 it will be understood that in 15 the first instance the inner extremity of the gage is applied to the open end of the casing of the tire valve, which open end will engage the compressible or elastic material 14 around the cup-shaped part 12, while the 20 perforated portion of the part 12 will act upon the valve stem to unseat the valve. As the outer end of the casing of the tire valve is sealed by virtue of its engagement with the elastic material 14, the air released by 25 unseating the valve will pass through one or both of the perforations 10 through the air filter 16 into the tube and into engagement with the plunger 9, the fluid passing also beyond the plunger so that the pressure on 30 both sides of the plunger is equalized, except as to an area equal to the cross section of the gage bar. The plunger and gage bar will then be moved outwardly under the influence of the air pressure, the said movement being frictionally retarded, the friction 35 gradually increasing, due to the fact that the inwardly bent or upset parts 8 of the tube gradually increase in degree from the inner to the outer extremity of the tube. The 40 gage bar, as illustrated in the drawing, is provided with numbers increasing by a common difference of ten, from 20 near the outer extremity of the bar to 100 near the inner extremity thereof. The instrument will be 45 properly calibrated and the figures will be placed on the bar in accordance with such calibration.

While in Figs. 1 and 2 the tube is provided with two depressions or inwardly offset wedge-shaped parts, it will be understood 50 that a greater number of these parts may be employed if desired. It should also be understood that various other constructions may be resorted to, some of which are set forth in the drawing in order to obtain the necessary gradual increase in friction as the plunger moves outwardly in the tube under the influence of the air pressure of the tire tube or other receptacle containing the fluid 55 pressure to be measured or registered.

In Fig. 3 exteriorly convex washers 26 and 27 are employed on opposite sides of the plunger, their object being to gradually draw in the edges of the periphery of the 60 plunger as the nut is tightened. In this way

a slight contraction of the plunger circumferentially, particularly as to the edges, may be attained.

In the form of construction shown in Fig. 5, the base or inner extremity of the tube is 70 provided with a cap 29 of somewhat different construction than that shown in the other views heretofore described. The inner extremity of the tube enters a circumferential groove 30 formed in the base and is secured in place. A circular cavity annularly arranged within the outer part of the cap contains a quantity 31 of elastic or compressible material as rubber, which is utilized in sealing the outer extremity of the 80 casing (not shown) of the tire valve, while the central part 32 of the cap forms a receptacle for the air filtering material 16, the part of the cap which retains the filtering material in place having perforations 33. 85 The elastic material 31 is exteriorly exposed, but will be packed or forced into its annular cavity in such a manner that it will be retained sufficiently securely for all practical purposes. 90

In the form of construction shown in Figs. 5 and 6 the plunger is composed of a metal disk 34 which is secured to the inner extremity of the gage bar 36 by a screw 35. In this case the tube 37 is cylindrical in 95 shape and attached to allow the circular plunger to move freely therein, but the gage bar tapers from its inner extremity outwardly and passes through an opening formed in a quantity of compressible or elastic material 38 held in the outer extremity of the tube by a ring 39, the outer end of the tube having a relatively large gage bar opening 40 to make room for the gradually increasing cross section of the gage bar as the 100 latter moves outwardly. In this case, the friction necessary for the proper performance of the function of the device is obtained by the contact of the wedge-shaped or tapering gage bar with the compressible or elastic 105 material 38. In this case a perforation 41 is formed in the plunger disk 34 to allow the fluid under pressure to pass to the opposite side of the plunger from the inlet side. 110

In the form of construction shown in 115 Figs. 7 and 8 the construction of the tube and the exterior tapering shape of the gage bar are substantially the same as shown in Figs. 5 and 6, but in Figs. 7 and 8 the gage bar is hollow and devoid of a separate plunger, its lower part extending into the cap and having an outwardly turned circumferential flange 42, the gage bar in its entirety being designated by the numeral 43. In this case the air under pressure enters the cap 120 through perforations 33 as in Fig. 5 and passes into a hollow gage bar whose cavity is open at the bottom and closed at the top. The flange is perforated, as shown at 44, to allow the pressure to equalize on both sides 125 130

of the flange between the tube and the hollow tapering bar. Thus, in this form, as in the other forms, the effective pressure area is equal only to that of the cross section of the gage bar.

In the form shown in Figs. 9 to 12 inclusive, the tube 45 is cylindrical in shape at the bottom or its inner extremity while above such extremity it is elliptical in shape, 10 the ellipsoidal form increasing from its inner to its outer extremity. In this form of construction the plunger 9 is compressible or elastic and the gradually increasing friction results from the continual change of shape 15 of the normally circular plunger into the ellipsoidal shape of increasing degree as the plunger moves outwardly under the influence of the fluid pressure, the lower or inner extremity of the tube being substantially the 20 same as shown in Fig. 1.

In Figs. 13 to 15 inclusive, the plunger 46 is rigid, being preferably composed of metal and is perforated as shown at 47 to receive the arms 48 of a spring yoke, the said arms 25 gradually approaching each other as they extend outwardly from the base, their outer extremities being connected by a semicircular part 49. As the plunger moves outwardly under the influence of the fluid pressure, the 30 arms 48 are separated by virtue of the yielding capacity of the part 49, such part offering the resistance which results in the necessary increasing friction between the plunger and the arms 48 of the yoke.

In the form of construction shown in Fig. 35 17, the tube 50 constitutes the frustum of a cone and gradually tapers from its inner to its outer extremity, while the plunger 9 which is of the same form as shown in Fig. 40 1 is elastic or compressible and the necessary increase in friction is obtained between the contact surfaces of the plunger and the engaging inner surface of the tapering tube.

In the form shown in Figs. 18 and 19 the 45 tube 51 is cylindrical throughout its length and there is arranged therein a quantity of compressible or elastic material 53 which is open to receive the rigid plunger 52. The opening or cavity gradually tapers from the 50 inner toward the outer extremity of the elastic material 53, whereby the necessary increase in friction is obtained as the plunger moves outwardly under the influence of the fluid under pressure. In this form of 55 construction the plunger is provided with a perforation 54; and a disk 55 which engages the inner extremity of the tube surrounded by the cap 56, the disk having a central projection 57 which passes through but does 60 not fill an opening 58 formed in a washer 59 preferably composed of rubber and forming an elastic seat for the outer extremity of the tube or casing of the tire valve for sealing purposes. In this case the projection 57 65 acts upon the stem of the tire valve to unseat

the valve piece while the air under pressure passes through the opening 58 around the projection 57 and thence through a layer 60 of felt or other suitable filtering material after which it enters the chamber 61 through 70 a perforation 62. As the plunger 52 and the gage bar move outwardly, the plunger compresses the elastic material 53 and as the thickness of this material increases from the inner to the outer extremity of the tube the 75 friction is correspondingly increased, thus giving the desired result on the principle of all other forms of my improved device. In this case the elastic material 53 within the tube itself constitutes a seal at the outer extremity of the tube around the gage bar.

In the form of construction shown in Figs. 22, 23 and 27 the quantity of elastic or compressible material 63 is arranged within the tube 64 which is cylindrical in shape. 80 The elastic material 63 is substantially of the same shape as in Fig. 18, being comparatively thin at the inner extremity of the tube and increasing in thickness toward its outer extremity. At the outer and inner extremities of the elastic or compressible material 63 are respectively arranged disks 65 and 66 which form anchors for the opposite extremities of a series of tapering plates 76 which form a metal armor for the elastic 90 material 63, whereby the metal plunger 67 as it moves outwardly in the gradually diminishing cavity acts upon the plates 76 thus bringing two metal surfaces in contact with each other for frictional purposes. The opposite extremities of the armor plates 76 are respectively provided with reduced projections 68 and 69. The projections 68 engage radial slots 70 formed in the outer disk 65 while the projections 69 engage anchoring recesses 71 formed in the disk 66. In this form of construction the air will 100 enter the inner extremity of the tube in the usual manner and act upon the plunger 67 which may be perforated as shown in other forms, to allow the air or other fluid to occupy the outwardly tapering cavity on both sides of the plunger. As the plunger moves outwardly the armor plates 76 gradually expand or open against the backing of 110 compressible material 63 between the armor plates and the inner surface of the tube. In this way the necessary increase in friction is 115 obtained between two metal surfaces.

In the form of construction shown in Fig. 120 24 a compressible plunger 78 is exteriorly armored by a series of metal clips 79 which are spaced to compensate for the compression of the disk during its outward movement in contact with any of the forms of 125 tube heretofore described in which compressible or elastic plungers are employed. In this case the elastic material is applied to a central metallic disk 80 to which the gage bar 17 is also secured. The clips 79 are nor- 130

mally sufficiently open to slip freely over the edge of the elastic plunger 78 but are afterward clenched by pressing their inner extremities toward each other sufficiently to 5 hold them securely in place upon the elastic material.

In the form shown in Figs. 20 and 21, the tube 81 tapers from its inner to its outer extremity and the plunger 82 which is secured 10 to the gage bar 17 is reduced in size so that it shall not be larger than the smallest inner diameter of the tube. This plunger member is perforated to receive the lower extremity of the gage bar and to the latter, below the 15 plunger, is attached by a nut 83 a yielding yoke 84 having a number of spring arms 85 which engage the tapering inner surface of the tube and the pressure on these arms gradually increases as the plunger moves 20 outwardly in the tube, whereby the necessary increasing frictional resistance results in order to carry out the principle of my improvement.

From the foregoing explanation the operation of the various forms of my improvement in a general way will undoubtedly be clearly understood; and while I have shown a number of forms or embodiments of the invention, it is evident that the invention embraces 25 a great many forms other than disclosed. Hence, the invention is not limited to details of construction except as set forth in the appended claims.

In my improved device, I prefer to employ a suitable lubricant for the surfaces of the frictionally contacting parts in order to prevent possible sticking of the parts and in order to promote uniformity in the increase of the friction during the outward 40 movement of the plunger and gage bar. The importance of some lubricating substance is particularly great where rubber or its compounds or similar elastic or compressible material is employed as one of the friction surfaces. This lubricant may consist of any suitable material either in powdered form, in liquid or in semi-liquid form. Powdered graphite or other anti-frictional material in powdered form, as plumbago, mica, powdered 45 aluminum or soapstone may be advantageously employed. If used as a dry powder within the chamber or cavity in which the plunger travels, provision should be made to prevent its working into any of the orifices of the device which must be kept 50 open for the passage of air. This function may be accomplished by a layer of felt or other suitably porous material adapted to form an air filter. This feature is illustrated 55 in Fig. 18, the element 58 forming a protection against the passage of the powdered material into the opening or orifice through which the air under pressure enters the instrument.

60 However, instead of using the powdered

lubricating substance in dry form it may be mixed with glycerin or other suitable liquid in order to prevent its sifting into the orifices of the device. It must be understood, however, that the invention is not limited to the 70 employment of the lubricant specified since any suitable or desirable substance in any convenient or appropriate form may be used. It is also evident that the lubricant feature may be omitted altogether without in any 75 way departing from the spirit of the invention.

Having thus described my invention what I claim is:

1. A tire gage, comprising a tubular member open at one end to receive fluid under pressure and having a cavity therein, a plunger movable in said cavity and in frictional engagement with the member, the two parts being constructed and arranged to 80 gradually increase the friction as the plunger moves from the open end in predetermined degree having definite and predetermined relation to the extent of movement, and a gage bar on which said plunger is mounted, there 85 being a passage connecting the portions of said cavity on opposite sides of the plunger, whereby the effective pressure area is equal only to that of a cross section of the gage bar. 90

2. A tire gage comprising a tubular member open at one end to receive fluid under pressure, a plunger member movable in said tubular member and in frictional engagement therewith, a gage bar connected to said 100 plunger and movable therewith, and means for retarding the travel of the plunger and gage bar from said open end by gradually increasing the friction in predetermined degree having predetermined relation to the 105 extent of movement under increase of pressure.

3. A gage of the class described comprising a tubular member, a plunger therein, a gage bar connected to said plunger, said bar 110 having a graduated part, the tubular member being open at its inner end for the entrance of fluid, and at the outer end for the reception of the graduated part of the said gage bar, the latter being arranged to be actuated by the fluid under pressure, the device including means for retarding the outward travel of the said plunger by gradually increasing the friction in predetermined degree having predetermined relation to the extent of movement under increase of pressure. 115

4. The combination of a tubular member, a plunger movable therein, a gage bar connected to said plunger, the tubular member being open at one end for the entrance of 120 fluid under pressure and at the other end for the projection of the gage bar, and means for retarding the travel of the plunger from said open end by gradually increasing friction in predetermined degree having prede- 125

terminated relation to the extent of movement under increase of pressure, the entire cavity within the tubular member being in communication with said fluid entrance whereby the 5 effective pressure area is equal only to that of a cross section of the gage bar.

5. A gage of the class described comprising a tube open at one end to receive fluid under pressure, and gage means movable 10 within the tube and comprising a graduated member, and a member coöoperating with the tube to gradually increase the friction as the said gage means moves in the tube from its open end in predetermined degree having 15 predetermined relation to the extent of movement under increase of pressure.

6. A device of the class described comprising a tubular means, and gage means including a bar, said gage means being movable in 20 said tubular means in frictional contact therewith, said parts being shaped to cause the friction to continually increase as the gage means moves from the fluid receiving end of the tubular means, one of said means 25 being yielding and the other rigid, the tubular means being open at one end to receive fluid under pressure and at the opposite end for the projection of the gage bar.

7. The combination of a tube open at one 30 end to receive fluid under pressure, a gage bar and a plunger secured to the inner extremity of the bar and in frictional contact with the tube, which is shaped by having its 35 sectional area decrease from said open end to the other to increase the friction as the plunger moves from said open end.

8. In combination in a tire gage, a hollow member open at one end to receive fluid under pressure, a gage bar member and a friction 40 member, the transverse dimensions of one of said members being gradually varied from one end of the device to the other to increase friction gradually as the friction member moves from said open end.

45. 9. The combination of a tube open at one end to receive fluid under pressure, a gage bar and a plunger secured to the inner extremity of the bar and in frictional contact with the tube which is shaped to increase the 50 friction as the plunger moves therein from said open end in predetermined degree having predetermined relation to the extent of travel.

10. The combination of a tube open at one 55 end to receive fluid under pressure, a gage bar extending within the tube and a plunger secured to the inner extremity of the bar and in frictional contact with the tube which is shaped to increase the friction as the plunger moves from said open end, the plunger 60 being perforated to allow the motive fluid to pass from one side of the plunger to the other to occupy the tube on both sides of the plunger.

11. The combination of a tube having an 65 opening at one end to receive fluid under pressure, a gage bar extending within the tube and a plunger secured to the inner extremity of the bar and in frictional contact with the tube, the latter having a longitudinal 70 indenture in its outer face increasing in depth from the fluid receiving end toward the opposite end of the tube, forming an interior rib of counterpart shape.

12. The combination of a tube having an 75 opening at one end to receive fluid under pressure, a gage bar extending within the tube and a compressible plunger secured to the inner extremity of the bar, the tube being formed with an interiorly projecting 80 longitudinally disposed area increasing in depth from its fluid receiving end toward its outer extremity and engaging the plunger in frictional relation.

13. The combination of a tube having an 85 opening at one end to receive fluid under pressure, a gage bar extending within the tube, a compressible plunger secured to the inner extremity of the bar, and longitudinally disposed means in the tube increasing 90 in transverse dimensions from the fluid receiving end to the other and engaging the plunger in frictional relation to increase the friction as the plunger moves from the fluid receiving end. 95

14. A device of the class described comprising a tubular means and gage means, the latter consisting of a gage bar proper and a plunger in frictional contact with the tubular means, the gage bar part having a 100 reduced extremity passing through the plunger part, metal washers applied to the plunger part on opposite sides and a nut threaded upon the reduced part of the gage bar for securing the parts in coöoperative relation, the washers being shaped to change the form of the plunger part as the said nut is adjusted, the plunger part being sufficiently yielding for the purpose. 105

15. A gage of the class described comprising a tubular member, a plunger therein including a gage bar proper, the tubular member being open at its inner end for the entrance of fluid and at the outer end for the passage of the gage bar part of the plunger 110 member, the latter being arranged to be actuated by the fluid under pressure, the tubular member being shaped to retard the outward travel of the plunger member by gradually increasing the friction, and means for sealing the outer extremity of the tubular member around the protruding gage bar. 115

16. The combination of a tube having one end open to receive fluid under pressure, a gage bar, and a plunger secured to the inner 120 extremity of the bar and in frictional contact with the tube which is shaped by having its sectional area decrease from said open 125 end.

end to the other to increase the friction as the plunger moves from said open end, the plunger being perforated to allow the motive fluid to pass from one side thereof to the other to occupy the tube on both sides of the plunger.

17. The combination of a tube having one end open to receive fluid under pressure, a gage bar extending within the tube and a plunger secured to the inner extremity of the bar and in frictional contact with the tube, the tube being shaped by having its transverse dimensions varying from one end to the other to increase the friction as the plunger moves from said open end.

18. The combination of a tube having one end open to receive fluid under pressure, a gage bar extending within the tube and a plunger secured to the inner extremity of the bar and in frictional contact with the tube, the tube being shaped by having its transverse dimensions varying from one end to the other to increase the friction as the plunger moves from said open end, the plunger being perforated to allow the motive fluid to pass from one side thereof to the

other to occupy the tube cavity on both sides of the plunger.

19. A device of the class described, comprising tubular means having an opening at one end to receive fluid under pressure and gage means movable therein and in frictional contact therewith, the relative sizes and shapes of the two means being such that the friction increases continually in predetermined degree having predetermined relation to the movement of the gage means from the fluid receiving end under increase in pressure.

20. A device of the class described comprising a hollow member having an opening at one end to receive fluid under pressure, a gage bar movable therein, a plunger connected to said gage bar and friction means coöperating with said plunger to increase the friction in a predetermined degree in accordance with the movement of said plunger from the fluid receiving end under increase in pressure.

In testimony whereof I affix my signature. 50

ARTHUR B. LOW.
